Primary Examiner — Brett Miller*Assistant Examiner* — Jessica M Gebhart(74) Attorney, Agent, or Firm — Womble Bond Dickinson (US) LLP(57) CLAIM

We claim the ornamental design for an outdoor shade, as shown and described.

DESCRIPTION

FIG. 1 is a perspective view of an outdoor shade;

FIG. 2 is a side view of an outdoor shade;

FIG. 3 is a top view of an outdoor shade; and,

FIG. 4 is a bottom view of an outdoor shade.

The dash-dash lines in the Figures represent unclaimed elements that form no part of the claimed design.

1 Claim, 4 Drawing Sheets(56)
